ART OF CRACKING HYDROCARBONS

Edward W. Isom, Scarsdale, N. Y., assignor to
Sinclair Refining Company, New York, N. Y.,
a corporation of Maine

Application October 12, 1929, Serial No. 399,227

4 Claims. (Cl. 196—49)

This invention relates to improvements in the cracking of heavier and higher boiling hydrocarbon oils, such as kerosene, gas oil, fuel oil or residues, to produce lighter and lower boiling hydrocarbon oils, such as gasoline or gasoline-containing cracked distillates, therefrom. This application is in part a continuation of my prior application filed May 21, 1927, Serial No. 193,192.

This invention provides an improved operation including in combination pressure distillation operations producing residues and intermediate character products which the pressure distillation operation itself is not particularly adapted to handle and another cracking operation particularly adapted to handle both such residues and such intermediate character products.

Where gas oil is cracked for the production of gasoline or a gasoline-containing pressure distillate by pressure distillation, for example, the products of the operation may include a tar or residue and a refractory intermediate fraction such as the bottoms remaining on re-distillation or fractionation of the pressure distillate to separate the gasoline content thereof. This intermediate fraction is usually quite refractory, and in many pressure distillation operations its further treatment in the same operation would impose a burden greater than the benefit derived. Likewise, such tar or residue is of a character such that its further treatment in many pressure distillation operations involves difficulty due to excessive formation of pitch or carbon.

In accordance with this invention, such refractory intermediate stock from the pressure distillation operation is forced through a heating conduit into a receptacle from which vapors are taken off and subjected in this heating conduit to severe cracking conditions adapted to produce therefrom additional quantities of the desired gasoline product, and such tar or residue is supplied directly to this receptacle heated, entirely or largely, by the heat of the hot oil products discharged into it from the heating conduit. The intermediate character stock is thus subjected to appropriate conditions for its further cracking even though refractory and the tar or residue is thus also subjected to further cracking under conditions avoiding difficulties due to excessive formation of pitch or carbon.

The invention will be further described in connection with the accompanying drawing which illustrates, in a diagrammatic and conventional manner, in elevation and partly in section, an apparatus adapted for the practice of the com-

bined operation of the invention, but it is intended and will be understood that this further description and illustration are for the purpose of exemplification and that the invention is not limited thereto.

The pressure still illustrated comprises a bulk supply drum 1, a battery of heating tubes 2 arranged in a heating furnace 3, and circulating connections 4, 5 and 6 including a circulating pump 7 arranged for circulating oil from the bulk supply drum upwardly through the heating tubes and back to the bulk supply drum, the oil being heated to a cracking temperature in the heating tubes and vapors being taken off from the bulk supply drum under superatmospheric pressure. Higher boiling components of the vapors from the bulk supply drum 1 are condensed in the reflux tower 8 and returned to the circulating charge of oil in the pressure still. This condensation may be effected or controlled, for example, by regulated introduction of raw oil to be supplied to the pressure still into the upper end of the reflux tower. Intermediate boiling components of the vapors from the reflux tower 8 are condensed in the fractionating tower 9 and conveyed to the supply tank 10 through connection 11. This condensation may be effected or controlled, to produce directly a gasoline product of the desired boiling range, for example, by regulated circulation of an indirect cooling medium through a coil in the upper end of the fractionating tower or by regulated introduction of a direct cooling medium into the upper end of the fractionating tower or by both of these means. Vapors from the fractionating tower 9, including the gasoline product, escape to a conventional condenser and receiver through connection 13. Tar or residue is discharged from the bulk supply drum 1 through connection 12.

Pressure in the pressure still may be maintained and regulated by means of appropriate valves between the reflux tower and the fractionating tower, between the fractionating tower and the condenser, or beyond the condenser or receiver. In the cracking of gas oil to produce gasoline, for example, the pressure still may be operated under a pressure in the neighborhood of 100-300 pounds per square inch.

The bulk supply drum, the circulating connections, the reflux tower, the fractionating tower and the several hot connections are with advantage lagged or thermally insulated.

The other cracking still illustrated comprises a still or drum 15 and a heating conduit 16 ar-

ranged in a heating furnace 17. A body of oil, or of oil approaching coke, is maintained in the drum 15, usually under superatmospheric pressure, and a stream of oil from the supply tank 10 is forced through the heating conduit 16 into this body of oil, being heated to a high cracking temperature, 1000-1100° F. for example, in the heating conduit. The body of oil in the drum 15 is thus heated to a cracking temperature, 10 725-775° F. for example, by heat internally supplied by the hot oil products discharged from the heating conduit 16. The drum 15 is advantageously externally unheated; it may however be mildly heated externally by means of the furnace 18. Usually the furnace 18 is employed only in initiating operation.

Higher boiling components of the vapors from the drum 15 are condensed in the fractional condenser 19 and intermediate boiling components 20 of these vapors are condensed in the fractional condenser 20. These condensations may be effected or controlled, for example, by regulated circulation of raw oil to be supplied to the drum 15, a crude or a topped crude or a fuel oil for 25 example, through these fractional condensers in indirect heat exchange with the vapors therein. Condensate from condenser 19 may be either conveyed to the pressure still through connection 21 or conveyed to supply tank 10. Condensate 30 from condenser 20 is conveyed to supply tank 10. Vapors from the fractional condenser 20 including additional quantities of the gasoline product escape to a conventional condenser and receiver through connection 14. Tar or residue may be 35 discharged from drum 15 through connection 22.

Pressure in the drum 15 may be maintained and regulated by means of appropriate valves between the drum and the fractional condensers, between the fractional condensers, between the 40 fractional condensers and the final condenser or beyond the final condenser or receiver. In the combined operation of the invention, the drum 15 may be operated under a superatmospheric pressure lower than that prevailing in the pressure still, in the neighborhood of 50-150 pounds per square inch, for example, or under higher pressure. The drum 15, although less advantageously if a maximum production of a gasoline product is desired, may be operated under atmospheric or a slightly higher pressure. The heating conduit 16 may be operated under a pressure just sufficient to effect discharge of the hot oil products therefrom into the drum 15; or the heating conduit 16 may be operated under a 45 higher pressure and this pressure regulated and reduced by means of an appropriate valve between the heating conduit 16 and the drum 15.

The drum 15, particularly when externally unheated, the fractional condensers and the several hot connections are with advantage lagged or thermally insulated.

The pressure still illustrated may be one of a battery of several; branch connections 11', 12' and 21' are provided in the apparatus illustrated 65 for connection to other similar pressure stills of a battery of several.

In carrying out the invention in the apparatus illustrated, the pressure still may be operated, for example, as described in Letters Patent No. 1,598,136, granted to Sinclair Refining Company, August 31, 1926, on the application of Eugene C. Herthel. The reflux tower and the fractionating tower connected to the pressure still may be operated, for example, as described in applica- 70

tion Serial No. 3,987, filed January 22, 1925, by John E. Bell.

In carrying out the invention in the apparatus illustrated, an intermediate stock from the pressure still, in boiling range between the gasoline product from and the condensate refluxed to the pressure still, is forced through the heating conduit 16 in which it is subjected to severe cracking conditions adapted to produce additional quantities of the gasoline product therefrom, and the tar or residue from the pressure still is supplied to the drum 15 in which it is subjected to further cracking by the heat of the hot oil products discharged into this drum from the heating conduit. The drum 15 may be operated to 10 reduce to coke the residue accumulating therein, or to reduce this residue to a heavy flux or pitch, discharged as a liquid from the drum 15. Raw oil, gas oil for example, may be supplied to the pressure still through connection 23. Raw oil, 20 easily cracked raw oil or raw oil including residual components, heavy gas oil or fuel oil or crude oil or topped crude oil for example, may be supplied to drum 15 through connection 24. Raw oil, refractory raw oil, light gas oil or kerosene for example, may be supplied to tank 10 through connection 25. The stock supplied to the heating conduit 16 includes in admixture the intermediate stock from the pressure still and the condensate from condenser 20 or from condensers 19 and 20, and may include additional raw oil supplied through connection 25. The stock supplied to the drum 15 includes the tar or residue from the pressure still and may include additional raw oil supplied through connection 24. 30

The improved combined operation of the invention improves the pressure distillation operation included in the combination in several respects. The invention makes it possible to relieve the pressure still of the burden of handling refractory components of intermediate stocks produced in the pressure still without prejudice to stock economy and at the same time makes it possible to relieve the pressure still of an increased part of the burden of handling pitch components of tar or residue produced in the pressure still without prejudice to operating economy but rather with joint advantage with respect to stock economy and operating economy. 50

It will be apparent that the invention, in one aspect, provides an improved method of further cracking pressure still tar and particularly of further cracking pressure still tar under superatmospheric pressure. It will also be apparent 55 that the invention, in another aspect, provides an improved method of narrowing the range of stocks which the pressure still must handle to that range over which it is most effective.

I claim:

1. In combination with pressure distillation operations for the manufacture of gasoline by cracking heavier and higher boiling hydrocarbon oils, the improvement which comprises taking off from the pressure distillation an intermediate stock 65 higher boiling than the gasoline product and lower boiling than the stock subjected to the pressure distillation and a tar including pitch constituents produced in the pressure distillation, forcing this intermediate stock through a heating conduit 70 and heating it to a high cracking temperature therein and discharging the hot oil products from this heating conduit into a separate receptacle from which vapors are taken off, and introducing this tar directly into this receptacle and there 75

cracking it further by the heat of the hot oil products discharged from the heating conduit.

2. In combination with pressure distillation operations for the manufacture of gasoline by cracking heavier and higher boiling hydrocarbon oils, the improvement which comprises taking off from the pressure distillation an intermediate stock higher boiling than the gasoline product and lower boiling than the stock subjected to the pressure distillation and a tar including pitch constituents produced in the pressure distillation, forcing this intermediate stock through a heating conduit and heating it to a high cracking temperature therein and discharging the hot oil products from this heating conduit into a separate receptacle from which vapors are taken off, and introducing this tar directly into this receptacle and there cracking it further under superatmospheric pressure by the heat of the hot oil products discharged from the heating conduit.

3. In combination with pressure distillation operations for the manufacture of gasoline by cracking heavier and higher boiling hydrocarbon oils, the improvement which comprises taking off from the pressure distillation an intermediate stock higher boiling than the gasoline product and lower boiling than the stock subjected to the pressure distillation and a tar including pitch constituents produced in the pressure distillation, forcing this intermediate stock through a heating conduit and heating it to a high cracking temperature therein and discharging the hot oil products from this heating conduit into a separate receptacle from which vapors are taken off, and introducing this tar directly into this receptacle and there cracking it further entirely by the heat of the hot oil products discharged from the heating conduit.

forcing this intermediate stock through a heating conduit and heating it to a high cracking temperature therein and discharging the hot oil products from this heating conduit into a separate receptacle from which vapors are taken off, and introducing this tar directly into this receptacle and there cracking it further under superatmospheric pressure by the heat of the hot oil products discharged from the heating conduit.

4. In combination with pressure distillation operations for the manufacture of gasoline by cracking heavier and higher boiling hydrocarbon oils, the improvement which comprises taking off from the pressure distillation an intermediate stock higher boiling than the gasoline product and lower boiling than the stock subjected to the pressure distillation and a tar including pitch constituents produced in the pressure distillation, forcing this intermediate stock through a heating conduit and heating it to a high cracking temperature therein and discharging the hot oil products from this heating conduit into a separate receptacle from which vapors are taken off, and introducing this tar directly into this receptacle and there cracking it further under superatmospheric pressure entirely by the heat of the hot oil products discharged from the heating conduit.
